UNITED STATES PATENT OFFICE.

JOHN W. SEAVER AND THOMAS R. MORGAN, OF CLEVELAND, OHIO,
ASSIGNORS TO THE WELLMAN-SEAVER-MORGAN ENGINEERING
COMPANY, OF CLEVELAND, OHIO, A CORPORATION OF OHIO.

GAS-PRODUCER.

SPECIFICATION forming part of Letters Patent No. 734,472, dated July 21, 1903.

Application filed September 20, 1902. Serial No. 124,238. (No model.)

To all whom it may concern:

Be it known that we, JOHN W. SEAVER and THOMAS R. MORGAN, both citizens of the United States, and residents of Cleveland, 5 Ohio, have invented certain Improvements in Gas-Producers, of which the following is a specification.

The object of our invention is to so construct a gas-producer as to provide for the 10 automatic discharge of the ashes from the ash-hopper and the breaking up of clinkers or compacted masses of ashes contained in said hopper, so as to permit of the ready discharge of the same. These objects we attain 15 in the manner hereinafter set forth, reference being had to the accompanying drawings, in which—

Figure 1 is a vertical section of a gas-producer constructed in accordance with our invention. Fig. 2 is a sectional plan view of the same on the line *a a*, Fig. 1. Fig. 3 is a perspective view of certain elements of the device. Fig. 4 is a sectional plan view on the line *b b*, Fig. 1; and Figs. 5 and 6 are respectively a side elevation and a sectional plan view illustrating a certain feature of our invention.

The producer has a vertical cylindrical body with heavy base-ring 1, cylindrical metal 30 shell 2, and refractory lining 3, the upper portion of the body having a depending sealing-ring 4, which projects into the water or other sealing agent in an annular sealing-pan 5, the latter depending from the fixed cover- 35 plate 6 of the producer, which has the usual gas-uptake flue 7 and feed-spout 8.

Suitably secured to the base-ring 1 of the producer-body is an annular rail 9, preferably made in sections bolted together, as 40 shown in Fig. 2, this rail running upon conical rollers 10, whose shafts are mounted in suitable bearings in posts or standards 11, secured to the main bed or foundation 12 of the producer, one of these standards also carrying a bearing 13 for a shaft 14, which is 45 rotated either continuously or intermittently in any suitable manner and is provided with a bevel-pinion 15, which meshes with a rack 16, formed upon the annular rail 9, whereby 50 either continuous or intermittent rotative

movement can be imparted to the body of the producer.

Suitably secured to the base-ring 1 of the producer is a depending ash-hopper 17, also by preference consisting of an annular shell 55 made in sections bolted together, as shown in Fig. 2, this shell being slightly conical or tapering inwardly from top to bottom and having at its lower end depending hooked arms or brackets 18, which carry an ash-supporting plate or platform 19, located at any desired distance below the bottom of the hopper 17, so as to provide free lateral outlet for the ashes between the two. In connection with the ash-hopper and ash-supporting plate 60 we may employ a sealing-pan 20, surrounding the lower portion of the ash-hopper, as shown in Fig. 1, and adapted to contain water or other sealing agent, or the entire lower portion of the ash-hopper, the ash-supporting 65 bed, and the posts or standards 11 may be contained within a sealing-pit of larger area, if desired.

Through the central opening in the ash-supporting bed or plate 18 passes a vertical blast-pipe 21, provided at the top with a conical hood 22 and connected at the bottom by an elbow 23 to a lateral blast-pipe 24, and suitably secured to this blast-pipe are arms 25 and 26, two of each of these arms being shown 70 in the present instance. The arms 25 are substantially horizontal and occupy a position close to or in contact with the upper surface of the ash-supporting bed or plate 19, and these arms are curved transversely, as shown 75 in Fig. 2. The arms 26 are curved upwardly, their vertical portions projecting into the mass of ashes contained in the lower portion of the ash-hopper 17.

The ash-hopper and the ash-supporting 80 plate or bed 19 are caused to rotate with the body of the producer, and a like rotating movement is therefore imparted to the mass of ashes contained within the hopper and resting upon the plate. Hence the stationary 85 arms 26 will exercise a stirring and disintegrating effect upon the mass of ashes contained within the hopper, so as to break up clinkers or compacted bodies of ashes contained in said mass, while the arms 25 will 90

have the effect of moving the mass of ashes outwardly upon the supporting bed or plate 19, so as to eject the same through the space intervening between the bottom of the ash-hopper and the said supporting bed or plate, the ashes entering the sealing-pan 20 or other sealing-pit and being removed therefrom in any convenient manner.

The blast-pipe 21 is supported upon a central base-casting 27, resting upon the foundation 12, and is connected thereto by a slip-joint, such as shown in Fig. 4, the pipe having projecting lugs 28, which are passed through slots 29, communicating with the central opening in said base-plate, the pipe being then turned so as to carry its lugs 28 out of line with the slots and into position to rest upon the base-plate or in suitable sockets therein, as illustrated in Fig. 4.

In Figs. 5 and 6 we have illustrated a plan of connecting the arms 25 and 26 to the blast-pipe which permits of the ready application or removal of said arms. In this case the blast-pipe carries a sleeve 30, which has projecting sockets 31 for the reception of the heads at the inner ends of the arms 25 and 26, the sockets being slotted for the reception of the arms and being open at the top, so that the arms can be applied or removed by a vertical movement of the same and will be secured in place without the use of bolts, nuts, or like fastenings.

The use of the stirring or disintegrating arms 26 may in some cases be dispensed with and only one of the arms 25 may be used, although it is preferable to use at least two of these arms in order to equalize the strain upon the blast-pipe, which carries the same.

Having thus described our invention, we claim and desire to secure by Letters Patent—

1. The combination of a gas-producer having a rotatable and depending ash-hopper and an ash-supporting bed or plate located below said hopper and rotating therewith and providing a space between them, and one or more stationary arms for pushing the ashes outwardly through the space between the bottom of the ash-hopper and the ash-supporting plate as the same are rotated, substantially as specified.

2. The combination of a gas-producer having a rotatable and depending ash-hopper and an ash-supporting bed or plate located below said hopper and rotating therewith and providing a space between them, one or more stationary arms for pushing the ashes outwardly through the space between the bottom of the ash-hopper and the ash-supporting plate, and one or more stationary arms projecting up into the ashes in the hopper, substantially as specified.

3. The combination of a gas-producer having a rotatable and depending ash-hopper and an ash-supporting bed or plate located below the bottom of said hopper and rotating therewith and providing a space between them,

and a fixed blast-pipe projecting up from said plate and carrying one or more arms for pushing the ashes outwardly through the space between the bottom of the ash-hopper and the ash-supporting plate, substantially as specified.

4. The combination of the body of the gas-producer having a rotatable and depending ash-hopper and an ash-supporting plate located below the bottom of said hopper and rotating therewith and providing a space between them, and a fixed blast-pipe projecting up through the ash-supporting plate and carrying one or more arms for pushing the ashes outwardly through the space between the bottom of the ash-hopper and the ash-supporting plate and one or more arms projecting upwardly into the mass of ashes in the hopper, substantially as specified.

5. The combination of the body of the gas-producer having a rotatable and depending ash-hopper, with an ash-supporting plate suspended from said hopper and located below the bottom of the same, so as to provide a passage for the escape of ashes between the two, substantially as specified.

6. The combination of the ash stirring or ejecting arms having enlarged heads, with a supporting structure therefor having open-topped sockets for the reception of said enlarged heads of the arms, substantially as specified.

7. The combination of the ash stirring or ejecting arms having enlarged heads, with a supporting structure therefor having open-topped sockets for the reception of said enlarged heads on the arms, said sockets being slotted for the reception of the arms, substantially as specified.

8. The combination of the vertical blast-pipe of a gas-producer having projecting lugs thereon with a base-plate having a central opening for the reception of said blast-pipe, and slots communicating with said opening for the passage of the lugs on the blast-pipe, substantially as specified.

9. The combination of the body of the gas-producer having a rotatable and depending ash-hopper and an ash-supporting bed or plate located below said ash-hopper and rotating therewith and providing a space between them, one or more stationary arms for pushing the ashes through the space between the bottom of the ash-hopper and the ash-supporting bed or plate, and a stationary sealing pan or pit surrounding the ash-hopper and receiving the ashes ejected therefrom, substantially as specified.

In testimony whereof we have signed our names to this specification in the presence of two subscribing witnesses.

JOHN W. SEAVER.
THOMAS R. MORGAN.
